Application November 5, 1942, Serial No. 464,643,
 which is a division of application Serial No.
 333,759, May 7, 1940. Divided and this applica-
 tion September 6, 1943, Serial No. 501,437

6 Claims. (Cl. 261—69)

1

This invention relates to carburetors for internal combustion engines and more particularly to improvements in downdraft carburetors of the plain tube type.

This application is a division of my application, Serial No. 464,643, filed November 5, 1942, which is a division of my application, Serial No. 333,759, filed May 7, 1940 which has now issued as Patent No. 2,328,504.

In devices, such as automotive carburetors, which utilize a diaphragm for actuating or sealing a metering valve or other movable part, it has been necessary to completely dismantle the diaphragm in order to inspect or replace the valve or part carried thereby.

It is the main object of the present invention to facilitate applying and removing a valve or other diaphragm operated device which is located behind the diaphragm.

A more detailed object is to provide means for sealingly attaching a metering valve to its actuating diaphragm in a manner to permit insertion and withdrawal of the valve through the diaphragm and without the necessity of disassembling the diaphragm.

Further objects and advantages of the present invention will be hereinafter set forth in the following specification and accompanying drawings, in which like numerals indicate identical parts.

Fig. 1 is a vertical center section of an automotive carburetor embodying the invention.

Fig. 2 is a horizontal section taken on line 2—2 of Fig. 3.

Fig. 3 is a vertical section taken on line 3—3 of Fig. 1.

Fig. 4 is a vertical section taken on line 4—4 of Fig. 1.

Fig. 5 is a detailed view of the metering rod and attaching screw.

In the drawings, numeral 1 indicates a main carburetor body casting having a suitable flange 2 formed at the lower end thereof for attaching a carburetor to the intake manifold of an internal combustion engine. A mixing conduit 3 is formed in the main body casting, and an adjacent constant level fuel chamber 4 is cast integral therewith. A portion of the mixing conduit 3 has a Venturi form as indicated at 3a which converges to the constriction or throat 5. The upper end of body casting 1 is provided with a smooth flange surface to which is attached an air inlet casting or air horn 6 and a fuel bowl cover 7 by means of attaching screws 8. Depending from the air horn casting 6 and projecting into the upper end of the mixing conduit are two concentric Venturi

2

tubes 9 and 10, Venturi tube 9 being arranged to discharge near the throat of venturi 10 and venturi 10 being arranged to discharge near the constriction 5.

5 The outlet 11 of the mixing conduit is controlled by a plate-type throttle valve 12 which is rigidly attached to a throttle shaft 13 by means of screws 14. Throttle shaft 13 is journaled in the bosses 15 and 15a. For operation of the throttle valve, 16 a stamped throttle operating lever 16 is rigidly attached to one end of the throttle shaft 13. The throttle lever 16 is fabricated from sheet stock by stamping and forming, and is provided at one end with a perforation 17 to receive a remote control rod (not shown). The throttle lever is normally urged toward a throttle closing position by the usual throttle pull back spring (not shown), which generally forms a part of the remote control linkage. Lever 16 is also provided with a pair of parallel bent-up portions 18 and 19 (Fig. 2), which are perforated and internally screw threaded to receive a throttle lever adjusting screw 20. Provision of adjusting screw 20 permits a fine adjustment of the throttle valve when in a near closed or idling position. An upper wing lug 21 on body casting 1 provides a throttle closing limit abutment, and a lower wing lug 21a provides a throttle opening limit abutment. A narrow tank 22 formed as part of lever 16 abuts lug 21a as the throttle valve reaches its open limit.

20 The air inlet passage 25 is controlled by a plate-type choke valve 26 which is eccentrically mounted for rotation with the choker shaft 27 which, 25 in turn, is journaled in the bosses 28 and 29. A pair of abutments 26a within the air inlet passage and cast as an integral part of the air horn casting 6 provide a wide open stop for the choke valve. Referring to Fig. 3, the left end of choker shaft 27 projects into a casing 30 which is cast as an integral part of the air horn casting 6. The casing 30, together with the cup-shaped cover 31, form a housing which completely encloses mechanism for the automatic control of 30 the choke valve 26.

25 Cast as an integral part of the fuel bowl cover 1 is a combination fuel inlet and vent boss 82. Boss 82 is provided with a comparatively large, horizontal bore 83 in which is retained a cylindrically formed wire screen retainer 84. Fuel entering through bore 83 passes through screen 84 and through a horizontal passage 89 to a vertical passage 90, see Fig. 4. The lower end of 35 passageway 90 is screw threaded to receive a

needle seat member 91, through which is provided a bore 92 to admit fuel to the fuel chamber 4. A conventional float 93 pivoted at 94 acts upon the needle valve 95 in a well known manner to maintain a constant level of fuel in chamber 4 substantially as indicated by the line $x-x$. Fuel is supplied to the carburetor mixing conduit for normal and full speed and load operation of the engine through a metering jet 96, through passages 97 and 98 and is discharged through nozzle 99 into the primary Venturi tube 9. Fuel for low speeds or idling operation is also metered by jet 96 and passes into passage 97 from whence it passes through the idling jet tube 100 and suitable passages to the usual idling ports adjacent the edge of the throttle when closed.

The amount of fuel available for aspiration from the main nozzle 99 and the idling ports is varied in accordance with engine intake manifold vacuum and throttle position by a stepped and/or tapered metering rod 109 extending axially into metering jet 96. As the metering rod 109, Fig. 3, is moved toward the left, the net opening of jet 96 is decreased. To position the rod 109 in accordance with manifold vacuum, a flexible diaphragm member 110 is rigidly attached to rod 109 at its center by means of the plunger member 111. Referring to Fig. 3, the left hand side of diaphragm 110 is subjected to intake manifold suction by reason of passages 112, 113, 114 and 115 which open as a port 116 in the wall of the mixing conduit below the throttle valve. The recess 117 in the carburetor body casting and the generally cup-shaped cover plate 118 form a working chamber for the diaphragm. The recess 117 communicates with the fuel chamber 4 through a large passage 117a, see Figure 2, so that the pocket of fuel therein and the diaphragm are in substantially unrestricted communication with the remainder of the bowl. The cover plate 118 firmly clamps the periphery of the diaphragm and is attached to the body casting by means of screws 119. The central perforation of cover plate 118, wherein is fitted for reciprocation the plunger 111, is provided with a packing gland 120. The plunger 111 passes through a central perforation in diaphragm 110 and is firmly attached thereto by riveting or spinning over the reduced end of the plunger as indicated at 121.

Plunger 111 is further provided with a through axial bore of sufficient size to permit the passing of the entire metering rod and is provided with internal screw threads 122a at its outer end. An externally threaded sleeve 122, staked to the rod, as at 123, Fig. 5, is secured in the plunger. It will be seen from the foregoing that the metering rod 109 may be removed or assembled without the necessity of removing the cover plate 118 and diaphragm 110. Metering rod 109 is normally urged to the right, Fig. 3, by the lever 124 which is acted upon by a spring 125. The lever 124 is carried on pivot 126 which also forms a pivot for a second lever 127 which is, in turn, connected to a lever 128 by means of a link 129. Lever 128 is rigidly attached to the throttle shaft 13.

Relative motion of levers 124 and 127 is prevented in one direction by the finger 131 carried by lever 124. It will be understood that spring 125 is so proportioned and calibrated with relation to the effective area of diaphragm 109 that the desired position of the metering rod for a given manifold vacuum is attained. From the foregoing, it will be seen that sufficient vacuum applied to the left side of the diaphragm 110 will

move metering rod 109 to the left; that, normally, the metering rod is urged to the right by spring 125 and that a clockwise rotation of the throttle shaft 13 (which is a throttle opening movement) will forcibly move the metering rod to the right in a less restricting position in jet 96.

It will also be noted that a movement to the right of diaphragm 110 caused by a drop in manifold vacuum or throttle opening movement will 10 displace the fuel in chamber 117, causing an increased pressure on jet 96 and also momentarily raising the fuel level in the constant level chamber. This enriching effect is highly desirable.

Fuel for acceleration is supplied to the mixing conduit under pressure by the diaphragm type accelerating device generally indicated at 132, Figs. 2, 3 and 4, and which comprises a circular chamber 133 formed by a recess in the main body casting and by the recessed cover 134 which 15 is attached thereto by means of attaching screws 135. A flexible diaphragm member 136 firmly clamped at its periphery between cover 134 and the carburetor body is provided and forms a partition in chamber 133. The diaphragm 136 is attached at its center to a horizontal plunger 137 which passes through the cover 134 and projects therefrom. A spring 138 bearing at one end against a retainer 139 and at its other end against cover 134 normally urges the diaphragm 136 and plunger 137 toward the right, Fig. 3, which is an intake stroke. A rocker arm 140 pivoted at one end at 141 and having attached at its other end at 150 a spring 142 which is connected to lever 128 moves the plunger and diaphragm to the left (discharge stroke) as the lever 128 is rotated clockwise (throttle opening direction).

It will be understood that spring 142 is substantially stronger than spring 138 and that its provision in lieu of a non-yielding link results in a smooth yielding pressure being exerted upon the plunger and diaphragm 136 which is desirable.

The accelerating device further comprises inlet passageways 151 and 152, Figs. 2 and 3, leading from the constant level fuel chamber 4 to the expansible chamber 133. A cylindrically formed wire mesh strainer 153 is provided and is retained in passage 152 by the screw threaded inlet check plug 154. The inlet check plug 154 is provided with a valve seat 155, a disc check valve 156 and a valve retainer 157. The fuel is discharged from chamber 133 through passages 158, 159, diagonal passage 160 and an accelerating jet (not shown) into the mixing conduit. A discharge valve seat is formed at the lower end of passage 159 at 162 by a reduction in diameter, and a gravity seating ball check valve 163 is provided and adapted to engage seat 162. The upper end of passage 159 is screw threaded and receives a screw plug 164 which is provided with a downwardly extending stem 165 which limits the upward movement of ball check 163 when the same is acted on by discharge pressure.

A decided advantage gained by the present arrangement of the accelerating device is that, by extending the discharge passageway upwardly from the very top of the expansible chamber 133 to a point above the fuel level, pressures which frequently build up in chamber 133 due to vaporization are released without the forcing of fuel from the chamber as occurs in many constructions. This advantage has particular significance due to the importance of maintaining a full charge of fuel in the accelerating chamber.

Referring to Fig. 1, a comparatively large vertical passageway 169 is provided, extending from the main fuel passage 98 to a point above the fuel level. The upper part of this passage communicates with the mixing conduit through a tube 170. This provision has the purpose of relieving vapor pressures at the base of nozzle 99, and its operation is fully described in my copending application, now Patent No. 2,234,946.

The operation of the carburetor is as follows: Fuel is supplied to the float chamber 4 through inlet passage 83, screen 84, and passages 89, 90 and 92 wherein a substantially constant level as indicated by line $x-x$ is maintained by the action of the float 93 on needle valve 95.

Fuel for normal and high speed operation is supplied to the mixing conduit from fuel chamber 4 through metering jet 96, passages 97, 98 and nozzle 99. During comparatively light load operation, the intake manifold suction will act on diaphragm 110 to move metering rod 109 toward the left, Fig. 3, that is, toward a more restricting position. The position of the metering rod under these conditions will also be determined by the throttle position. When sufficient load is applied to the engine for any given throttle position to cause a sufficient resulting drop in manifold vacuum, spring 125 will urge the metering rod toward the right to a less restricting position.

Fuel for idling operation is supplied to the mixing conduit from fuel chamber 4 through jet 96, passage 97, idling jet 103, idling tube 100, passages 101 and 102, and is discharged into the mixing conduit near the upward opening edge of 35 throttle valve 12 through the usual idling ports (not shown).

Fuel for acceleration is supplied under pressure to the mixing conduit from the accelerating chamber 133 during the discharge stroke of diaphragm 136, through passages 158, 159, and 160. The diaphragm 136 is actuated through its discharge stroke by an opening movement of the throttle valve by means of linkage comprising the rocker arm 140, the spring 142, and lever 128.

When the throttle is suddenly opened from nearly closed position, pressure in the carburetor outlet and in diaphragm control passages 112 and 113 increases, causing rapid inward movement of diaphragm 110 by spring 125. This forces liquid fuel back through open bowl communication 117a, momentarily raising the level in the bowl, and through main metering jet 96. Additional fuel is thus supplied to the mixture conduit through the main nozzle, both because of the raised level and consequent increased pressure in the bowl and because of the extra charge of fuel forced directly into the main nozzle passage. As the throttle is opened, the distance diaphragm 110 can move because of a drop in suction to the carburetor becomes progressively less, since the diaphragm is impelled inwardly by lever 124 operated by the throttle. This is an advantage because less auxiliary pick-up fuel is needed for acceleration from a substantially open throttle position than from a nearly closed throttle position.

The invention is not limited in details to the structure shown, but may be modified in various respects as will occur to those skilled in the art and the exclusive use of all such modifications as come within the scope of the appended claims is contemplated.

I claim:

1. In a carburetor, a mixture conduit, a main fuel passage, a constant level fuel chamber hav-

ing a lateral extension below the fuel level and opening through the side wall of said chamber, a diaphragm closing said opening and acting against the fluid in said chamber, a plate fixed over said diaphragm and forming a suction chamber therewith, said plate having an opening axial of the center of said diaphragm, a suction passage connecting said conduit and said chamber, a metering orifice in said main fuel passage, a metering pin for regulating the fuel passing through said orifice, said metering pin extending axially through said orifice, diaphragm, and plate opening, and means removable through said plate opening and securing said metering pin to said diaphragm whereby movement of said diaphragm by suction regulates the flow of fuel through said jet.

2. The substance of claim 1, further including guide structure for said metering pin in a portion of the carburetor wall spaced from said diaphragm.

3. In a carburetor, a mixture conduit, a fuel bowl forming a constant level float chamber formed on one wall of said conduit, the common wall between said conduit and said chamber being thickened, a main fuel nozzle passage extending from the lower part of said bowl through said common wall and opening into said mixture conduit, a fuel nozzle arranged in said nozzle passage and extending into said mixing conduit, a pocket formed in the wall of the lower part of said float chamber and in open communication therewith, a suction responsive diaphragm forming one wall of said recess, a passageway formed in said thickened wall connecting said nozzle passage and said recess, a metering orifice in said passageway, a metering valve secured to said diaphragm and extending through and controlling said metering orifice, and guide means closely fitting a portion of said valve, said guide means being aligned with said passageway.

4. In a carburetor, a mixture conduit, a fuel bowl forming a constant level float chamber formed on one wall of said conduit, the common wall between said conduit and said chamber being thickened, a main fuel nozzle passage extending from the lower part of said bowl through said common wall and opening into said mixture conduit, a fuel nozzle arranged in said nozzle conduit, a pocket formed in the wall of the lower part of said float chamber and in open communication therewith, a suction responsive diaphragm forming one wall of said pocket, said thickened common wall terminating short of said pocket at one edge to provide open communication between said pocket and said bowl, a passageway formed in said thickened wall connecting said nozzle passage and said pocket, a metering orifice in said passageway, a metering valve secured to said diaphragm and extending through and controlling said metering orifice, and guide means closely fitting a portion of said valve said guide means being aligned with said passageway and being positioned inward of said metering orifice.

5. In a carburetor, a mixture conduit, a fuel bowl forming a constant level float chamber formed on one wall of said conduit, the common wall between said conduit and said chamber being thickened, a main fuel nozzle passage extending from the lower part of said bowl through said common wall and opening into said mixture conduit, a fuel nozzle arranged in said nozzle passage and extending into said mixing conduit, 70 an opening in an outer wall of said float cham-

ber, a suction responsive diaphragm secured over said opening, a passageway formed in said thickened wall and connecting said nozzle passage and said float chamber, a metering orifice in said passageway, a metering valve secured to said diaphragm and extending through and controlling said metering orifice, and guide means closely fitting a portion of said valve, said guide means being aligned with said passageway and being positioned inward of said metering orifice.

6. In a carburetor, a mixture conduit, a fuel bowl forming a constant level float chamber formed on one wall of said conduit, a portion of the wall of said conduit adjacent said float chamber being thickened, a main fuel nozzle passage extending from the lower part of said bowl through said thickened wall portion and opening into said mixture conduit, a fuel nozzle arranged in said nozzle passage and extending into said mixing conduit, an opening in an outer wall of said float chamber, a suction responsive diaphragm secured over said wall opening and

formed with a central opening, a suction chamber formed over the outer face of said diaphragm including a wall formed with an opening in alignment with the opening in said diaphragm, a tube secured at one end portion to the wall defining the central opening in said diaphragm and movable with said diaphragm, the outer end of said tube extending through and closely fitting the wall defining the wall opening in said suction chamber, a passageway formed in said thickened wall and connecting said nozzle passage with said float chamber, a metering orifice in said passageway, a metering valve having one end portion extending into said tube and its other end portion extending through said metering orifice, means for adjustably securing said metering valve in said tube, and means engaging said valve to maintain its axis in constant predetermined relationship with the axis of said metering orifice.

GEORGE M. BICKNELL.
